BUILDING MECHANISM FOR PACKAGES
OF YARN

Gordon Haldane Pimley, Preston, England, assignor to Dobson & Barlow Limited, Bolton, England

Application October 1, 1949, Serial No. 119,042
In Great Britain May 11, 1949

2 Claims. (Cl. 242—158)

1

This invention has reference to building mechanism for package of textile yarns in textile machines wherein yarn is built into packages on bobbins, tubes or the like mounted on vertical spindles, by the up and down reciprocation or traverse of a device such as a ring rail, the general construction of such machines being well known and understood in the textile industry though the machines are not all alike in detail and are known under many names.

The present invention has for its object to provide improved mechanism for controlling the traverse of the ring rail or of the spindle rail which shall be more efficient than mechanism used at present for this purpose and which is especially useful for the building of large packages of rayon, though not limited to such use, whereby better packages are built and variations in the type and shape of the packages are easily and exactly effected, the mechanism being strong and of comparatively simple construction.

According to this invention yarn package building mechanism for textile machinery of the kind referred to comprises two stop members mounted on reciprocating members actuated by a suitable rotary part of the machine one at least of these stop members being automatically and progressively moved along the reciprocating members from zero to maximum and back during the running of the machine, whereby the two stop members engage and move arms on a direction controlling mechanism to reverse the direction of movement of the ring rail, or of the spindle rail at a predetermined position according to the setting of the mechanism.

The invention is more particularly set forth with reference to the accompanying drawings in which:

Fig. 1 is a front elevation of the mechanism.

Fig. 2 is an end elevation partly in section looking in the direction of the arrow in Fig. 1.

Fig. 3 is a plan of the compound lever.

Fig. 4 is a front elevation of the compound swinging arms.

Fig. 5 is a plan of Fig. 1.

Figs. 6, 7 and 8 are detail detached views of parts of the larger figures, immediately adjacent.

The building mechanism shown in the drawings is mounted at one end of the machine, the end plate 6 of which is shown in section in Figs. 2 and 8 but is not shown in Fig. 1: by mounting the mechanism on the end plate of the machine it is in a convenient position for its working and is easily accessible.

The mechanism has two parallel rods 7 above 55

2

and 8 below both slidably mounted in two brackets 9 and 10 (9 not being shown in Fig. 2) which are secured to the end plate 6 by nuts and bolts 11.

The rods 7 and 8 are mounted to slide parallel with the end frame plate 6 and are secured at the ends by bridge pieces 12 secured by bolts 13.

The bottom rod 8 has a toothed rack 14 on its under face engaged by a pinion 15 on a short shaft 16 at the other end of which is a sprocket, 10 wheel 17 driven by a chain 18 from a sprocket, not shown in the drawings, on the lifter shaft on the machine, which shaft, constantly changing its direction of rotation, in a manner described later herein, reciprocates the two rods 15 7 and 8.

Mounted on the rods 7 and 8 is a member 19 having an upwardly extending arm 20 secured to it at the top and having between the rods, a transverse extension 21 bored to form a bearing 20 for a short shaft 22 having on its back end a ratchet wheel 23 in front of which is a cam plate 24 with a cam groove in its front face, while at the front end of the short shaft 22 is a toothed shock wheel 25, having above it a 25 spring pressed pawl 26 which holds the wheel steady but can be over ridden when the wheel is turned.

The upward extending arm 20 which rises above the top edge of the cam plate 24 has 30 mounted in it at the top two compound swinging arms 27 shown separately in Figs. 3 and 4.

These arms are not of the same length, nor are they aligned, the longer arm 28 has a slot 29 and the shorter arm 30 angularly disposed 35 to the arm 28 as shown in Fig. 4 has an opening 31 in which a short stud is mounted carrying a roller 32 running in the cam groove 33 of the cam plate 24, the cam groove 33 being a heart shaped cam giving a straight line motion.

40 Mounted in the slot 29 of the other arm is a slider having on it a roller 34, the slider being adjustable at any position in the slot and held by the nut 35, and the roller is in a vertical slot 36 in a bridge member 37. On the bottom end 45 of the slider bridge member 37 is an adjustably mounted stop 38 and opposite but not in line is a similar stop 39 on a bridge member 40 slidably on the rods 7 and 8 when it is desired to move it, but normally held in a fixed position by a grub screw 41.

On the brackets 9 and 10 and at the back near the plate 6 is a bar 42 having slots 43 near its ends so that it can be adjusted to and fro as required and can be held by screwing down the 50 screws 44 whose shanks pass through the slots

43. This bar 43 has on it a spring pressed pawl 45 which is in line with the ratchet wheel 23: the pawl 45 can be adjusted up and down by altering the nut 46 on its top end.

The two adjustable stops 38 and 39 project downwardly as shown and while they are on the same level they are not opposite but are side by side. Each of these stops is designed to engage a separate lever 50 below when it—the pawl—is moving in one direction but not to operate it when moving in the other direction.

These levers serve, when operated, to reverse the direction of rotation of the lifter shaft, and the particular mechanism by which this is done is not part of the invention so long as the stop 38 when moving in one direction moves over a lever which reverses the direction of rotation, and the stop 39 when moving in the opposite direction engages its lever and reverses the direction of rotation, the two stops thus constantly reversing the direction of rotation; that is all that is required of them. It is convenient for the levers engaged to actuate electrical apparatus or other means to give the necessary rapid reversal.

When the machine is to be used, the size and shape of the packages to be wound are known and the mechanism is set accordingly, the position of the stop 39 fixing the bottom of the package, the stop which is movable, fixing the top of the package.

The invention can be used with a machine having either a rising and falling ring rail, the spindle level being fixed, or with rising and falling spindles, the level of the ring rail being fixed. For the purpose of this description, it will however be assumed that the ring rail rises and falls and the spindles do not. On this assumption the bridge 40 and the stop 39 carried by it are adjusted to the bottom of the package at which level the stop 38 reverses the direction of rotation of the lifter shaft so that the ring rail rises till the stop 38 engages its lever and again reverses the direction of rotation.

When a flat based package is to be built the reversal of direction of rotation at the bottom will always be at the same level so the stop 39 can be adjusted to the bottom position and fixed. The top of the package will, however be continually rising on the spindle until the maximum top position is reached, and consequently the other stop 38 must be movable so that it effects a reversal of the direction of rotation at different levels.

The required variation of the level of reversal effected by the stop 38 is effected by first slackening the nut 35 by which the roller 34 is held in its adjusted position in the slot 29 of the long arm of the compound lever 27. This allows the bridge member 37 to be slid to and fro on the rods 7 and 8 to the desired position, and the releasing of the roller which can thus move up and down the slot 29 and also the vertical slot 36 in the bridge member 27. When the desired adjustment of the position of the bridge member 37 has been made the nut 35 is secured to fix the position of the roller in the slot 29 and also, though it can slide up and down therein in the slot 36.

The position of the spring pawl 45 is adjusted as this pawl, which is in line with the ratchet wheel 23 will engage teeth of the wheel as it is moved to and fro by the reciprocation of the rods 7 and 8; in one direction the pawl turns the wheel and in the other it does not, but over rides

the teeth, the check pawl 26 holding the wheel 25 and through it the ratchet wheel 23. It will be appreciated that by moving the spring pawl 45 toward or from the ratchet wheel 25 the number of teeth the ratchet wheel can be "notched-on" by the pawl can be varied, within the adjustable limits.

When the machine is working, and considering Figs. 1 and 5, the rods 7 and 8 and all they carry are at one end of their travel, and they have moved to the left hand side. One of the stops 38 or 39 comes into operation at this point and the direction of the wheel 17 is reversed from the reversal of direction or rotation of the lifter shaft and the rods 7 and 8 move to the right and in due course the ratchet wheel 23 is engaged by the spring pawl 45 and is notched-on one or more teeth and turned. This turning also turns the cam plate 24 which moves the short arm 30 of the compound swinging arms 27, whose roller is in the cam groove, and it also moves the long arm 28 carrying the roller 34 slidably in the vertical slot 36 in the bridge member 37, and consequently the bridge member 37 and its stop 38 are moved to and from the stop 39.

The distance between the stops 38 and 39 is thus widened up to a maximum and then narrowed to a minimum and this movement continues as long as the machine is running. The position at which the stop 38 engages and operates the arm 50, which in some cases may be a switch arm, thus varies at each reciprocation of the rods and this in turn varies the top position of the ring rail or of the spindle rod, where the reversal of the movement is effected.

In this way the package is built up having a flat base and a tapered nose or top, the angle of the package nose or top being decided by the number of teeth the ratchet wheel 23 is notched on at each engagement with its pawl 45, and also by the adjustment of the sliding roller 34 in the bridge 37.

In order to avoid layers of yarn in the package from lying in the same positions at each traverse the ratchet wheel 23 is given an odd number of teeth by which the position of the yarn laid during the up movement is not exactly the same as in the down movement.

I claim:

1. A yarn package building mechanism for textile machinery comprising supports on the machine, two parallel rods one above the other and connected at their ends and slidably mounted in said supports, a toothed rack on the underside of the lower of said rods engaged by a rotating pinion, two brackets on said rods, stops on the bottom ends of said brackets, a member mounted on said rods and between said brackets, an upwardly extending arm on said member, a transverse extension on said member and between said rods, a transverse shaft rotatably mounted in said transverse extension, a ratchet wheel secured on the back end of said transverse shaft, a cam plate on the front of said ratchet wheel, said cam plate having a cam groove in its face, a spring pawl on said support engageable with and turning said ratchet wheel when moved in one direction against said pawl, a compound arm swingably mounted in said upwardly extending arm, one arm of said compound swinging arm having a roller in said cam groove, said other arm having a slot in which is adjustably mounted a roller, a groove in the back of one of said brackets in which said adjustably mounted

roller slides, said transverse shaft having at its front end a toothed check wheel engaged by spring pawl.

2. A yarn package building mechanism for textile machinery comprising supports on the machine, two parallel rods one above the other connected at their ends, a toothed rack on the underside of the lower rod engaged and said rods being reciprocated by a reversible pinion, two brackets on said rods, stops on said brackets each for engaging when moving in one direction only a lever for reversing direction of rotation of said reversible pinion, a member carried on said rods between said brackets, an upwardly extending arm on said member, a compound swing arm on said upwardly extending arm, a roller on one of said arms of said compound arms, a slot in the other arm, having an adjustable roller in it, a groove in the back of one of said brackets in which said adjustable roller runs, a transverse shaft on said member, a cam plate on said shaft having a groove in which said roller on the other arm of said compound swing arm runs, a ratchet wheel on said shaft, mounted above said ratchet wheel on said supports an adjustable bar, an adjustable

5

spring pawl on said adjustable bar in line with said ratchet wheel, and according to its adjustment notching on said ratchet wheel one or more teeth at each movement in one direction of said rods whereby said ratchet wheel and cam are turned in intermittent movements, said compound arm being accordingly moved on said rods whereby the position at which said stop on said bracket is progressively varied and as a result

10

the reversal of rotation of the machine is effected progressively.

spring pawl on said adjustable bar in line with said ratchet wheel, and according to its adjustment notching on said ratchet wheel one or more teeth at each movement in one direction of said rods whereby said ratchet wheel and cam are turned in intermittent movements, said compound arm being accordingly moved on said rods whereby the position at which said stop on said bracket is progressively varied and as a result

15

the reversal of rotation of the machine is effected progressively.

GORDON HALDANE PIMLEY.
